United States Patent Office

Des. 205,999
Patented Oct. 18, 1966

205,999

GRAVELING TRAILER

Antonio Guevara, Jr., and Joe O. Young, both of Houston, Tex., assignors to Layne & Bowler Inc., Houston, Tex., a corporation of Maryland

Filed Sept. 13, 1965, Ser. No. 86,960

Term of patent 14 years

(Cl. D14—3)

Fig. 2

FIGURE 1 is a perspective front view of a graveling trailer, showing our new design;

FIGURE 2 is a perspective rear view thereof; and

FIGURE 3 is a perspective side view thereof.

What we claim is:

The ornamental design for graveling trailer, as shown.

References Cited by the Examiner

UNITED STATES PATENTS

D. 171,566 2/1954 Wylie ----- D14—3

WALLACE R. BURKE, Primary Examiner.

CONRAD A. BOUSQUET, Examiner.

WILLIAM WERTMAN, Assistant Examiner.